UNITED STATES PATENT OFFICE.

TOD J. MELL, OF YOUNGSTOWN, OHIO, ASSIGNOR TO PERFECTION TIRE & RUBBER COMPANY, OF CHICAGO, ILLINOIS, A CORPORATION OF ILLINOIS.

DESIGN FOR A TIRE-TREAD.

51,072.

Specification for Design.

Patented July 24, 1917.

Application filed March 10, 1917. Serial No. 154,047. Term of patent 14 years.

To all whom it may concern:

Be it known that I, Tod J. Mell, a citizen of the United States, residing at Youngstown, in the county of Mahoning and State of Ohio, have invented a new, original, and ornamental Design for Tire-Treads, of which the following is a specification, reference being had to the accompanying drawings, forming part thereof, in which the figure is a fragmentary plan view of a tire embodying my design.

Reference being had to the drawing forming part of this application for Letters Patent, the numeral 1 indicates a portion of the tread surface of an ordinary pneumatic tire-casing which is, of course, of the usual annular form.

Extending circumferentially and centrally around the tire tread 1 is a continuous series of cruciform figures 2 in relief, the longitudinal, or centrally arranged, arms of which terminate in close proximity to each

other, and the transversely arranged arms of which terminate adjacent the opposite sides of the tire tread as shown.

In each of the substantially rectangular spaces thus produced upon opposite sides of the longitudinal center of the tread, and between each pair of transverse arms of adjacent figures 2 aforesaid, are provided inversely arranged letters P as indicated by the numeral 3. These letters 3 like the figures 2 aforesaid, are of unitary structure, and are formed as an integral part of the tire tread surface.

I claim:

The ornamental design for a tire tread as shown and described.

In testimony whereof I affix my signature in the presence of two subscribing witnesses.

TOD J. MELL.

Witnesses:

B. E. BROOKS,
ARLIE M. FOOR.
